CYLINDRICAL PRESS STRUCTURE

Johan A. Muller, Mount Gilead, Ohio, assignor
to The Hydraulic Development Corporation,
Inc., Wilmington, Del., a corporation of Delaware

Application October 24, 1940, Serial No. 362,634

35 Claims. (Cl. 100—71)

1

This invention relates to presses, and in particular to the main body of a press comprising the press head and press bed.

Heretofore it was standard practice in the building of presses with a press head and press bed to cast the head and the bed of a press separately and to connect the same by means of strain rods. Such castings include very heavy projecting lugs through which the strain rods pass and which cause such variations in thickness of the sections that it is very difficult to get a sound casting. Furthermore, considerable machining is required for providing the shoulders on the castings for the strain rods and for boring the holes through which the strain rods are passed. In addition to the expensive material required for the said strain rods, the assembling and proper locating of the strain rods and of the bed and head castings takes considerable time, thereby further increasing the cost of production of such presses.

It is, therefore, an object of the invention to provide a press body comprising a press head and press bed which is simple in construction, relatively cheap to manufacture, and makes it possible materially to reduce the time heretofore required for assembling the various press members.

It is another object of the invention to provide a press comprising a press head and press bed, in which the strain rods heretofore required for spacing and connecting the head and bed of a press are eliminated.

It is a further object of the invention to provide a press of the type set forth above, in which the press head is directly placed upon the press base.

A still further object of the invention consists in the provision of a press body with a press head and press bed, in which the press head and press base are cast as a single unit of fairly uniform section and may be machined from one end of the casting in one machining setup.

It is still another object of the invention to provide a press with a press bed and press head, in which the press bed and press base constitute a single cast unit with a longitudinal cored bore therethrough, which bore is open at one end and closed at the other end and has apertures intermediate said ends for allowing the insertion of the press platen.

It is a still further object of the invention to provide a press of the type set forth in the preceding paragraphs, in which the press base comprises a multiple part press bed.

Another object of the invention consists in

2

providing a press body with integral press head and press base, which has simplified means for guiding the press platen and allows of said guiding means being machined with the same machining setup which is used for machining the cylinder bore in the press body.

Still another object of the invention consists in the provision of a press body in which the press head is integral with a solid press bed.

10 These and other objects and advantages of the invention will appear more clearly from the following specification in connection with the accompanying drawings, in which:

Figure 1 is a perspective view of the press body according to the invention.

Figure 2 shows a first embodiment of the invention partly in section along the line 2—2 of Figure 3.

Figure 3 is a section along the line 3—3 of Figure 2.

Figure 4 illustrates a section along the line 4—4 of Figure 2.

Figure 5 shows a modification of the lower part of the press body illustrated in Figure 2.

25 Figure 6 is a section along the line 6—6 of the press body shown in Figure 7 and constitutes a further embodiment of the invention.

Figure 7 shows a section along the line 7—7 of Figure 6 in which, however, the press ram and press platen are not shown in section to indicate the outer contour thereof.

30 Figure 8 is a still further embodiment of the invention showing the press head and press bed as separate castings which are directly superimposed upon each other.

Figure 9 is an embodiment somewhat similar to Figure 8, in which the press head and press base are connected with each other by a kind of bayonet joint.

40 Figure 10 shows an exploded view of the bayonet joint used in the structure of Figure 9.

Figure 11 shows, on a somewhat smaller scale, the method of assembling the press bed of the structure illustrated in Figure 9.

45 Figure 12 shows a detail of the invention.

Figures 13 to 19 illustrate a convenient manner of assembling the press platen and press bed in a press body according to the invention.

Figure 20 shows a section through a still further embodiment of the invention.

Figure 21 is a view of a still further embodiment of the invention, which embodiment allows the employment of a circular platen and has provision for a simplified assembly thereof in the

Figure 22 is a vertical section through Figure 21.

Figure 23 is a section along the line 23—23 of Figure 22, and

Figure 24 is a section along the line 24—24 of Figure 22.

Referring to the drawings in detail and in particular to the embodiment of Figure 2, the press body illustrated therein comprises a press head 1 and press base 2 which are integral with each other and preferably cast as a single unit. The press head 1 carries a fluid storage tank 3 which is connected with the press head in 3 which is connected with the press head in any convenient manner. The press head 1 has a cylinder chamber 4 with a cylinder bore 5, 15 in which the press ram 6 is reciprocably mounted and which is adapted to communicate through a surge valve 7 with the fluid tank 3. The surge valve 7 does not form a part of the present invention and for a more detailed description thereof reference may be had to U. S. Patent No. 2,193,248 to Walter Ernst. The purpose of the surge valve 7 is to prefill the cylinder chamber 4 and cylinder bore 5 at the beginning of the downward stroke of the press ram 6. The press head 1 is furthermore provided with an inlet 8 communicating with a conduit 9 for supplying pressure fluid from a pressure fluid source (not shown) to the cylinder chamber 4. To prevent leakage from the cylinder chamber 4 and cylinder bore 5 toward the outside, a packing 10 is provided compressed by a gland 11. As will be seen from Figure 4, the gland 11 is made up of a plurality of segments, 11a, 11b, 11c and 11d, which are connected to the shoulder 12 of the press head by means of screws 13 and are inter-connected by connecting members 14 which are fastened to two adjacent segments by means of screws 15 and connected to the shoulder 12 by screws 16.

The press ram 6, which is provided with hollow chambers 17 and bores 18, has a central circular recess 19 with a centering disc 20 therein, a portion of which extends into a recess 21 provided in the press platen 22 which is adapted to support a die (not shown). The disc is intended to properly locate the press platen 22 with regard to the press ram 6.

The structure of Figure 2 is provided intermediate the press head and press base with lateral windows 23, 24, having machined edges 25 serving as guiding surfaces for gibs 26 connected in any convenient manner, for instance by screws 27, with the press platen 22. The width of the windows 23, 24 is such as to allow insertion of the press platen 22 with its smaller sides through said windows, while the length of the platen 22 is greater than the width of said windows. Provided in the lower surface of the press platen 22 and connected therewith in any convenient manner are wear plates 28, preferably provided with a curved portion 29, adapted to be engaged by the correspondingly shaped upper portion of a push back plunger 30. The push back plunger 30 is reciprocably mounted in a push back cylinder 31 which is connected by means of its flange 32 and screws 33 with hollow segments 34. To prevent leakage from the push back cylinder 31 toward the outside, a packing 35 compressed by a gland 36 is provided. The segments 34 which may in part be inserted into the press base through the opening 37 thereof and through the windows 23, 24, are provided with a shoulder 38 adapted, when properly located, to engage a correspondingly

shaped shoulder 39 in the press base. The segments 34 are furthermore provided with a shoulder 40 for receiving and locating a central or cylindrical member 41, which is of such diameter as to allow its insertion into the press body through the windows 23, 24. If desired, means such as a key or pin may be provided for preventing an accidental turning movement of the central or cylindrical member 41. Similarly, the segments 34 are held in their position by keys, pins or the like. The central member 41, together with the segments 34, constitutes the press bed which is adapted to support a work piece.

After the casting comprising the press head 1 and press base 2 has been properly machined on its inside for receiving the press ram 6, press platen 22 and segments 34, the different press members can easily be inserted into the casting 20 in any desired manner. A convenient method for assembling the various press members is illustrated in Figures 13 to 16. According to this method the casting comprising the press head 1 and press base 2 is placed upside down with the top part on the floor. The ram 6 is then lowered in position through the opening 37 which is slightly greater than the diameter of the press ram in order to provide the necessary clearance therefor. Thereupon the packing 10 is inserted 25 and the gland 11, in the present instance made up of four sections, is fastened to the shoulder 12 to hold the packing in place. After the ram and the gland are thus located, the centering disc 20 is inserted into the recess 19 of the ram. Now as indicated at Figures 14 and 15, the platen 22, 30 the width of which is less than the width of the windows 23 and 24, is passed with its smaller side portion through one of said windows and pushed over the ram bottom until its recess 21 is engaged 35 by the centering disc 20. The platen 22 is then given a one-quarter turn, as indicated in Figure 16, and the gibs 26 are fastened to the front and back of the platen so that they are adapted to slide along and be guided by the beveled surfaces 45 on the machined edges or surfaces 25. The casting 1, 2, can now be turned over so that the base 2 rests on the floor, while care is to be taken that the ram and platen will stay in their top position. With the press body in its proper position, the bed can now be inserted into the press base. To this end the segments 34 are inserted, preferably 50 through the windows 23, 24, into the press base and so located therein and connected therewith, that they define a cylinder. Then the lower part 55 of this cylinder is temporarily filled with blocks or a device like a jack which can be worked from below the floor level, whereupon the central member 41 is inserted through one of the windows 23, 24, and gradually lowered into the cylinder 60 defined by the segments until the cylindrical member 41 engages the shoulder 40 of the segments 34. After the cylindrical member 41 is secured against accidental turning movement in the segments 34, the push back cylinders 31, together 65 with the push back plungers 30, are lowered into the recesses or cores provided in correspondingly located segments and are fastened thereto by means of the flange 32 and screws 33. Finally, the surge valve 7 and the tank 3 are mounted on 70 the press head, while the cylinder chamber 4 and the push back cylinders 31 are connected with their pipes. As is usual in the press art, also stop members 42, not shown in Figures 4 and 5, are connected to the press bed in order to prevent the press platen 22, or a die connected there- 75

with, from a direct contact with the press bed or a die supported thereby if the platen 22 should accidentally slide downwardly.

As will be seen from the drawings, the press illustrated in Figures 1 to 4 has completely eliminated the strain rods heretofore required, and the press head and press base, including the press bed, are connected with each other through the cylindrical wall portions between the windows 23 and 24. The outer contour of the press is preferably cylindrical and practically without any laterally protruding portions so that the space required for the press body is reduced to a minimum. As previously mentioned, the press body comprising the press head and press base is made as a single casting with a cored longitudinal bore therethrough which is closed at the press head and open at the press base, and intermediate the press base and press head communicates with the outside by the cored windows. This structure, in addition to its rigidity and materially simplified shape, has the further advantage that the machining operations are practically reduced to boring and turning work. It should also be noted that due to the absence of laterally protruding wall portions of the press body heretofore required for the strain rods, and due to the fact that the press head and press bed are connected with each other by the wall of the press body, the horizontal distance between the axis of the press cylinder and the remotest point of the wall of the press body is reduced to a minimum, thereby materially decreasing the bending force exerted by the press ram on the wall of the press body.

As will be clear from the above description, the main casting comprising the press head and press base can be machined entirely in one setup from the base opening of the casting. The construction is such that a boring bar may be inserted into the casting which is used for driving the cutting tools supported by bearings or steady rests, one mounted outside of the base and the other mounted between the head and base section. Also the segments 34 and central member 41 can easily be machined by mere turning operations. Consequently, the press body as illustrated in Figures 1 to 4 considerably simplifies the construction and assembly of presses comprising a press head and press bed.

The advantages pointed out above also apply wholly or to a great extent to the remaining embodiments shown in the drawings.

Referring to Figure 5, the structure shown therein differs from the structure in Figure 2 merely in that the segments 34 and the central member 41 are replaced by a single cylindrical bed member 43 which on its periphery is provided with a thread 44 engaging a corresponding thread in the press base. The bed member 43 is properly located and held in its position by means of a pin or key 45, engaging a bore 46 in the press base and a bore 47 in the bed member 43. The diameter of the thread 44 may be at least as large as the diameter of the curved wall portions between the windows, in which wall portions the press platen reciprocates. This arrangement allows of the platen being inserted through the threaded bore in the press base. Otherwise the structure of Figure 5 corresponds to that of Figure 2.

With regard to Figures 6 and 7, the press body shown therein is similar to the press body of Figure 2 with the exception of the press bed. The parts of Figures 6 and 7 corresponding to

those of Figure 2 are, therefore, designated with the same reference numerals.

As will be seen from Figures 6 and 7, the press base 2 is provided with a cylindrical stepped bore 48 having an annular shoulder 49 on which rests the bed member 50. The contour of the upper portion of the bed member 50 is similar to the outer contour of the platen 22, as illustrated in Figure 18. The bed member 50 is also provided with openings 51 for receiving the push back cylinders 31 in the manner described in connection with Figure 2. Similar to the platen 22, the bed member 50 is inserted into the press body through the windows 23, 24, as shown in Figure 18, whereupon the bed member 50 is turned by ninety degrees, as indicated in Figure 19, and temporarily held in lifted position so that its upper portion can be reached through the windows 23 and 24. Now side members or segment pieces 52, having a curvature corresponding to the curvature of the bore 48, are inserted into the press base and connected with the bed member 50 in any convenient manner, for instance by screws 53. Thereafter the press bed composed of the bed member 50 and side members 52 is gradually lowered into the press base until it engages the shoulder 49 of the bore 48. After the press bed is so located it is prevented from accidental turning movements by a key or the like. The push back cylinders 31 may then be lowered into the press bed and fastened thereto, while stop members 54 are mounted on the press bed. As will be obvious from a comparison of Figures 6 and 7 with Figures 2 and 5, the bed structure of Figures 6 and 7 is somewhat simplified over that shown in Figures 2 to 5.

Figure 8 shows a further embodiment of the invention according to which the strain rods heretofore required for connecting the press head and press bed with each other are likewise eliminated. According to Figure 8, the press head 55 and press bed 56 are made as separate castings which are superimposed upon each other so that the press head directly rests upon the press bed. The press head and press bed are bolted together by bolts 57 passing through flanged portions 58 and 59 of the press head and press bed respectively. Since in this structure the platen 22 may be assembled in the press head before the lower portion of the press body comprising the press bed is flanged to the press head, the multiple part gland 11 may be replaced by a single piece gland 60. The remaining parts of the press illustrated in Figure 8 are similar to those of Figures 2, 6 and 7, and are designated with corresponding reference numerals.

Referring now to Figure 9, the structure shown therein likewise comprises a press head and press bed made as separate castings which directly engage each other. However, in contradistinction to the embodiment of Figure 8, the press head 61 rests directly, by means of its flange 62, upon the floor 63, while the press bed 64 with its flanged portion 65 is suspended on the bottom 66 of the press head 61. The assembly of the press bed 64 in the press head 61 will be clear from Figures 10 and 11, which show that the flanged portion 65 of the press bed 64 may be passed through a correspondingly shaped opening 67 in the bottom 66 of the press head and then turned by ninety degrees so that it will be supported by the bottom 66. As will be seen from Figure 11, the width of the flange portion 65 is smaller than the portion of the bottom 66 between the slotted portions 68 of the opening 67. In

order to prevent accidental turning movement of the press bed 64, the press bed and press head are connected with each other by bolts 68. It should be noted that the bolts 68 are merely locating means and may be replaced by a key or the like since any pressure exerted by the press ram on the press bed is transferred from the press bed through the flanged portion 65 to the bottom 66 of the press head. After the flanged portion 65 is thus properly located on the bottom 66 of the 10 press head 61, segment pieces 79 are inserted through the windows 23, 24, and are dropped between the flanged portions 65. The segment pieces 79 will then rest with their ends on the bottom 66 of the press head 61 since, as shown in Figure 11, 15 the segment pieces 79 are longer than the width of the slotted portion 80. The segment pieces 79 snugly fit between the flanged portions 65 so that they are held in their position by the latter. Figure 11 shows only one of the pieces 79 assembled, 20 while the other slotted portion 80 is still to be covered by a segment piece.

The press bed 64 of the structure shown in Figure 9 comprises, in addition to the flanged portion 65 and segment pieces 79, a plate 69 resting 25 with its shoulder 70 on the wall portion 71 of a cushioning cylinder 72 having reciprocably mounted therein a cushioning piston 73. The cushioning cylinder 72 is connected with pipes 74 and 75 adapted to supply pressure fluid to the cushioning cylinder and to discharge it therefrom. To prevent leakage from the cushioning cylinder 72, a packing ring 76 is inserted in the wall portion 71 of the cushioning cylinder 72 and supports packing material 77 compressed by a 30 gland 78. It is, of course, understood that the cushioning cylinder-piston-assembly 72, 73, may be omitted and the bed plate 69 rested directly on the bottom 66 of the press head 61. In this instance the bed plate 69 may be provided with 35 a flanged portion similar to the flanged portion 65, while the segment pieces 79 will then supplement the bed plate 69 as they do now with the flanged portion 65. Aside from the features just referred to, the press of Figure 9 is similar to 40 that of the remaining embodiments so that the various parts are designated with the same reference numerals as the corresponding parts in the previously discussed embodiments.

While in the structures described so far the press platen is guided along the surfaces 25 of the windows 23 and 24 by means of the gibs 26 connected to the press platen, the press platen 22 may be replaced by a press platen 81, as illustrated in Figure 12. As will be seen from the said Figure 12, the press platen 81 is guided, by means of its surfaces 82, along the surfaces 83 of the wall portion 84 of the casting comprising the press head. In this instance the wall portion 84 comprises recesses 85 so that only a small surface is to be machined for guiding the platen 81. This guiding arrangement for the press platen has the great advantage of further simplifying the machining of the press body, since the machining of the guiding surfaces for the platen can without difficulties be effected with the same machining setup which is provided for boring the press body. Any undesired rotation of the platen 81 may be prevented in this construction by stop members 86 connected by screws 87 with the wall portion 84. If desired, the machining of the press body adjacent the press platen may be omitted, in which case the inner diameter of the press body adjacent the press platen should be larger than the outer diameter of the guiding surfaces. 75

To guide the platen 81, gibs may be provided between the said wall portion of the press body and the guiding surfaces of the platen in a manner described later in connection with Figures 21 to 24. These gibs, which directly engage the circular guiding surfaces of the platen, are adjustable from the outside of the press body.

To facilitate the machining operation of the press bodies shown in the various figures of the drawings, the press body may, if desired, at its head portion be provided with a bore 88, through which the boring rod may be introduced or in which it may be guided. After the press body has been machined, the bore 88 is plugged, e. g., by a threaded bolt 89.

Referring now to Figure 20, the press body shown therein differs from the structure illustrated in the preceding figures in that it has a solid press bed; in other words, the press head, the press base and press bed constitute a single casting. In order to allow the machining of the press cylinder, the press head is provided with a bore 90, through which the bore rod may be introduced and which is closed in any convenient manner, e. g., by plug 91, after the machining is completed. Aside from the press bed, the structure of Figure 20 is similar to that of Figures 6 and 7, and windows are provided intermediate the press head and press bed through which the press ram and the press platen can be inserted into the press. The rim portion of the press bed can be machined with the general machining setup, while the remaining portion of the bed may then be machined through the windows. However, instead of the last mentioned operation through the windows, it may be preferable to provide a recess 92 in the bed casting and, after machining of the rim portion 93, to insert a bolster plate 94 which may be introduced into the press through the windows thereof. The shape of the bolster plate 94 is preferably similar to the bed member shown in Figure 19, which consists of a main member 50 and side members 52 attached to the main members by screws 53.

To reduce the weight of the press, the press bed is preferably provided with cavities 95 communicating with the recess 96 at the foot of the press.

Finally, referring to the embodiment shown in Figures 21 to 24, also in this embodiment the press head 1 and press base 2 are integral with each other. Similar to the embodiments of the previous figures, the fluid tank 3 is mounted on the press head, and surge valves 7 are associated with the press head to control the additional supply of fluid from the tank to the cylinder chamber 4, or the exhaust of fluid from the cylinder chamber 4 to the tank 3. The press is furthermore provided with a conduit 9 for supplying pressure fluid to actuate the press ram 6 which is operatively connected with the press platen 97. While in the previous embodiments the press platen is shown with two flat and two curved sides, the press platen 97 is completely circular. The diameter of the press platen 97 is not greater than the opening 98 in the press base, which opening is at least as large as the diameter of the ram 6. In this way the ram, as well as the platen, may be introduced into the press body through the opening 98. The opening 98 is closed by the press bed 99, having a larger portion 100 and a smaller portion 101, and resting with its larger portion on segment pieces 102, 103, which engage an annular recess 104 in the lower wall portion of the press body. Two push back cylinders 31

are supported by and connected with the press bed in a manner similar to the push back cylinders 31 in the previously described embodiments. However, while in the embodiments hereinbefore described the push back plunger merely engages the press platen but is not rigidly connected therewith, the push back plungers 105 in the embodiment of Figures 21 to 24 are connected, for instance, by screws, with the platen 97. Since accidental turning movement of the press bed 100 is prevented by positioning screws 106, accidental rotation of the platen 97 cannot occur due to the push back plungers connected with the platen and guided in the push back cylinders 105.

The embodiment of Figures 21 to 24 furthermore differs from the previously described embodiments in that the platen 97 is guided by segmental-shaped gibs 107 arranged in the bore portion 108. The gibs 107 may be adjusted and positioned in a desired manner by means of combined positioning and adjusting screws 109 which are preferably arranged in a staggered manner, as shown in Figure 21. The combined positioning and adjusting screws do not form a part of the present invention and for a more detailed description thereof reference may be had to U. S. Patent No. 2,336,351, to Flowers issued December 7, 1943. It is of course understood that, instead of the combined screws 109, any other positioning and adjusting screws may be provided.

The embodiment shown in Figures 21 to 24 is of particular importance with regard to a simplified machining of the press body and the members associated therewith and also enables a very simple assembly of the various members. In this connection it will be noted that all the machining necessary for the press body can be effected in one single machining setup, and the machining operations for the ram, the platen and the press bed are merely turning operations. To assemble the various members in the press body, the press body is first turned upside down as described in the previously mentioned embodiments, whereupon the ram 6, the packing 10, the circular gland 110, the platen 97 and the press bed 100 are introduced through the base opening 98. Thereupon the segments 102, 103 are inserted so that they engage the annular recess 104. Now the press is turned so that it will be standing on its base and after the bed 100 is properly located in the segments 102, 103 and spaced from the platen 97, the push back cylinders and pistons are assembled. The gibs 107 may then be inserted through the windows 23, 24 and properly positioned and adjusted by the screws 109 which extend through the wall of the press body and can be operated from the outside of the press body.

It will be understood that I desire to comprehend within my invention such modifications as come within the scope of the claims and the invention.

Having thus fully described my invention, what I claim as new and desire to secure by Letters Patent is:

1. A press comprising in combination a press head, a press base, a cylinder integral with and interconnecting said press head and press base, and a multiple part press bed mounted in said press base and composed of a central member and means laterally connected thereto for supplementing the supporting area of said central member.

2. In combination in a press, a single cast unit including a press head, a press base, and a cylindrical body interconnecting said head and said

base, said body being hollow and having an opening toward the outside intermediate said press head and said press base, a press plunger reciprocably mounted in said press head, a press platen operatively connected with said press plunger and reciprocable in said cylindrical body, and means associated with said platen and extending into said opening for guiding said platen.

3. A press comprising a hollow cylinder including a press head and a press base, said cylinder having an opening in its side wall intermediate the press head and press base, a press plunger movable in said press head, means for reciprocating said press plunger, and a press bed having a plurality of segmental ring portions and a central member adapted to be received and located by said ring portions.

4. A press body comprising a press head, a press base integral with said press head, and a press bed surrounded by said press base and detachably connected therewith, said press bed including a central cylindrical portion and means adapted to be interposed between said base and said cylindrical portion for locating the latter.

5. A hydraulic press comprising in combination a cylindrical hollow body, said body including a press head and a press base integral with one another, an opening in the wall portion of said cylindrical body intermediate said press head and said press base, a press ram reciprocably mounted in said press head, means for supplying fluid pressure to said press ram, a press bed mounted in said press base and composed of a central member and lateral members detachably connected thereto for supplementing the working area of said central member, each of said members being adapted to be inserted into said body through the opening in the side wall thereof.

6. In combination in a press, a press head including a cylinder, a press plunger reciprocably mounted in said cylinder, a press platen operatively connected with said press plunger, a cylindrical press base, a hollow cylindrical body integral with said press head and said press base and having a window between said head and said base, said window being slightly wider than the width of said platen, a press bed supported by said press base and including an element of a shape similar to the shape of said platen, and hydraulic means supported by said press bed and operatively connected with said press platen for actuating the same.

7. A press comprising a hollow cylindrical press body open at the lower end thereof, said body including a press head and a press base integral with one another and having windows in the wall portion of said body intermediate said press head and said press base, a press plunger reciprocably mounted in a cylinder formed by said press head, a press platen operatively connected with said press plunger, means for aligning said press platen with said press plunger, said press platen being adapted to be inserted into said body through said windows, means for guiding said platen in said body, and a press bed stationarily mounted in said press base.

8. A press comprising a hollow cylindrical body, open at one end and closed at the other end and having windows in its wall portions intermediate said ends, a press ram reciprocably mounted in said body adjacent the closed end thereof, a press platen operatively connected with said ram, a multiple part press bed adapted to be mounted in said body adjacent the open end thereof, the dimensions of certain of said bed parts being such

as to allow insertion thereof through the open end of said cylindrical body.

9. A press comprising a cylindrical body having integral therewith a cylindrical press head and a cylindrical press base, a press cylinder formed in said press head and having reciprocably mounted therein a press plunger, means for admitting pressure fluid to said cylinder to actuate said press plunger, a press bed surrounded by and mounted in a recess in said press base, a press platen operatively connected with said press plunger and guided by wall portions of said cylindrical body intermediate said press head and press base, said wall portions defining windows having a width only slightly greater than the width of said platen, so as just to allow insertion of said press platen therethrough with the narrow side thereof, and hydraulic motor means interposed between said press bed and said press platen for effecting a retraction stroke thereof.

10. A press comprising a cylindrical press base, a cylindrical press head spaced from said press base by curved wall portions integral with said press head and press base and defining windows therebetween, said press head including a cylinder having a press plunger reciprocably mounted therein, said press base being open at its end and being adapted to allow assembly of said press plunger through said opening, a press platen operatively connected with said press plunger and adapted to be inserted between said wall portions through said windows, said platen having two longer flat sides and two smaller curved sides with the curvature thereof corresponding to the inner contour of said wall portions, and means associated with said platen for guiding the latter between said wall portions.

11. A press comprising a press base, a press head spaced by cylindrical wall portions integral with said press head and press base and defining windows therebetween, said press base having an opening therein adapted to be closed by a press bed portion, a press ram reciprocably mounted in said press head and adapted to be assembled therein through said opening in the press base, a press platen operatively connected with said press ram and adapted to be inserted between said wall portions through the windows defined thereby, means associated with said platen and engaging said windows for guiding said platen, and hydraulic motor means interposed between said platen and said bed portion for actuating said platen.

12. A press comprising a cylindrical hollow body including a press head and press base integral with one another, windows in the wall portions of said hollow body intermediate said press head and press base, a press plunger adapted to be inserted into said press head through a cylindrical opening in said press base, a press platen having two flat portions and two curved portions, the curvature of which corresponds to the inner contour of the wall portions between said windows, said press platen being adapted to be inserted through said windows, a press bed having two flat portions and two curved portions, the curvature of which corresponds to the diameter of a bore in said press base, said diameter being greater than the diameter of said opening in said press base, while the distance between said flat sides of said bed is less than the width of said windows, and segments adapted to be connected with said bed along the flat portions thereof so as to fill in the space between

5 10 15 20 25 30 35 40 45 50 55 60 65 70 75 80 85 90 95

said flat portions of the bed and the adjacent curved wall portions of the bore in said base.

13. A press comprising a press head, a press base integral with said press head and forming a hollow body therewith, said body being closed at its upper end and having an opening in the bottom thereof, and a multi-part press bed some of the parts of which are adapted to be inserted from the outside through said opening in the base bottom so as to cause said bottom to support said bed.

14. A press body comprising a press head, an open press base integral with said press head and defining therewith a hollow cylinder, a multi-part press bed closing said open base, there being windows intermediate said press head and said press bed, said press head having a bore therein of a diameter sufficient to allow introduction of a boring rod therethrough, and means for closing said bore.

15. A press comprising in combination a press head, a press base having an opening therein and being spaced from said head by a cylindrical wall portion integral with said head and said base and having a window therein, and a multiple part press bed mounted in said press base, said press bed including a main member with arcuate ends and flat sides adapted to be assembled in said base through said opening, and also including segments adapted to be assembled through said windows and to supplement said main member to a circular bed.

16. In combination in a press, a press cylinder, a press ram movable in said cylinder, a press bed, a press base supporting said press bed and being integral with said press cylinder, said press base and press cylinder defining a bore with a window in its side wall, and a press platen movable in and confined by said bore and having its periphery on two opposite sides shaped in conformity with the contour of said bore, said window having a width greater than the width of said platen but less than the length of said platen.

17. A press comprising in combination a press cylinder, a ram movable in said cylinder, a bed, a base supporting said bed and being integral with said cylinder, said base and said cylinder defining window portions therebetween, a press platen having curved portions at its periphery and being operatively connected with said ram, and means detachably connected with said platen and engaging guiding surfaces on said windows for guiding said platen and preventing rotation thereof.

18. A press comprising in combination a press head, a press base having an opening therein and being spaced from said head by a cylindrical wall portion integral with said head and said base and having a window therein, and a multiple press bed mounted in said press base, said press bed including a cylindrical main member and subsidiary members engaging the wall of the press body and supporting said main member.

19. A press comprising in combination a press head, a press base having an opening therein and being spaced from said head by a cylindrical wall portion integral with said head and said base and having a window therein, a cylindrical press bed provided with an annular flange, and supporting members engaging an annular recess in said press body and supporting said flange of said press bed.

20. In combination in a press, a press base having a bore therethrough, a press head having a plunger reciprocably mounted therein, a cy-

cylindrical body integral with and interconnecting said press base and said head, and a press bed mounted in said bore, said press bed comprising a central member mounted in said bore, and means insertable through and mounted in said bore and interposed between said base and said central member for partially supporting the latter.

21. A press comprising a hollow cylindrical body, said body including a press head and a press base supported from each other by wall portions integral with both, a plurality of apertures in said cylindrical body, one of said apertures forming a bore through said press base and at least one other of said apertures forming a window in said wall portion, a press ram reciprocably mounted in said press head, a press platen operatively connected with said ram, a press bed mounted in and supported by said press base, said ram, said platen and said bed being adapted to be inserted through said apertures for assembly within said cylindrical body.

22. A press comprising, in combination, a press cylinder, a ram reciprocable in said cylinder, a press bed, a press base supporting said bed, said base and cylinder being integrally connected by portions having guide surfaces parallel to the direction of reciprocation of said ram, a platen connected to move with said ram and guided by and between said surfaces, and guide means attached to said portions and contacting said platen to limit the same to reciprocation along said surfaces.

23. In combination with a hollow press base, having an internal shoulder, a bed comprising a plurality of sector-shaped parts supported on said shoulder, and jointly defining a central opening, and a central base part fitting said opening and maintaining said sector-shaped parts in position.

24. In combination with a press base having a cylindrical shouldered opening therein, a plurality of sector-shaped base parts, said parts resting on the shoulder of said cylindrical opening and shaped to conjointly define a central shouldered opening, and a central member fitting said central opening and supported upon the shoulder thereof, all said parts having substantially coplanar upper surfaces to define a press bed.

25. In combination with a press base having a cylindrical shouldered opening therein, a plurality of sector-shaped parts resting on the shoulder of said opening throughout the complete circumference thereof, said parts being shaped to conjointly form a central shouldered cylindrical opening, and a center part fitting said center opening and resting on the shoulder thereof, all said parts coacting to form a press bed.

26. In a press, a single unitary casting having substantially cylindrical walls closed at one end to form a press cylinder, and having its other end open to form a press base, there being an opening in said walls between said head and base, and a multi-part press bed supported within said base and including at least one part insertable through said press base and a second part through said wall opening, said parts interfitting to form a rigid press bed.

27. A press body comprising a hollow cylinder closed at one end to form a head and also having a stepped opening at the other end forming a base, there being openings in the side walls of said cylinder between said ends and an opening

in said press head through which boring means may be introduced, and a press bed fitting said stepped opening and including interfitting sector-shaped parts resting upon the step of said opening.

28. A press comprising a unitary frame having an internal cylindrical surface closed at one end to form a press cylinder and having openings in its side walls defining guide edges parallel to the direction of reciprocation of a piston in said cylinder, a platen having projecting portions slidably fitting said cylindrical surface adjacent said edges, and gibs attached to said edges and contacting said platen to limit its movement to reciprocation along said edges.

29. A press comprising a one piece body having a bore extending from one end part way therethrough, the said bore having one diameter adjacent the open end of said body, a smaller diameter adjacent the closed end of said body and a larger diameter intermediate the said ends, window means in the wall of said body between the ends thereof, a press plunger reciprocable in the smaller portion of said bore, a press bed mounted in the larger diameter portion of said bore adjacent the open end thereof in order to close the said open end, a press platen operatively connected with said press plunger, and means for guiding said press platen on the wall portions of said body adjacent said window means.

30. A press comprising a hollow cylindrical body, said body including a press head and a press base supported in spaced relationship by a wall integral with both, a plurality of apertures in said body at least one thereof forming a bore through said base and at least another forming a window in said wall, a press ram reciprocably mounted in said press head, a press platen connected to reciprocate with said ram, a multipart press bed mounted in and at least partially supported by said press base, the said ram, platen and bed being adapted for insertion through said apertures for assembly within said cylindrical bore.

31. A press comprising a hollow cylindrical body, said body including a press head and a press base supported in spaced relationship by a wall integral with both, a plurality of apertures in said body at least one of which forms an axial bore through said base and another of which forms a window means in said wall, a press ram reciprocably mounted in said press head, a press platen connected to reciprocate with said ram, a press bed mounted in and at least partially supported by said press base, the said ram, platen and bed being adapted for insertion through said apertures for assembly within said cylindrical body, and other ram means carried between said bed and said platen for retracting the latter.

32. A press comprising a hollow cylindrical body, said body including a press head and a press base supported in spaced relationship by a wall integral with both, a plurality of apertures in said body at least one of which forms an axial bore through said base and another of which forms a window means in said wall, a press ram reciprocably mounted in said press head, a press platen connected to reciprocate with said ram, a press bed mounted in and at least partially supported by said press base, the said ram, platen and bed being adapted for insertion through said apertures for assembly within said cylindrical body, means spaced about the said wall portion and in engagement with said platen for guiding the latter in non-rotative reciprocation within said body, and other ram means supported by said bed

and engaging said platen for retracting the latter from said bed.

33. A press comprising a hollow cylindrical body, said body including a press head and a press base supported in spaced relationship by wall portions integral with both, a plurality of apertures in said body one of which opens through said base and at least another of which opens through said wall to form a window, a press ram reciprocably mounted in said head, a platen connected to be reciprocated by said ram, a press bed mounted in and supported by said press base, the said ram, platen and bed being adapted for insertion through said apertures for assembly within said cylindrical body, and ram means carried by said bed and reciprocable toward and away from the head end of said body.

34. A press comprising a hollow cylindrical body, said body including a press head and a press base spaced apart by a wall integral with both, a plurality of apertures in said body one of which opens axially through said base and at least another of which forms a window in said wall, a downward acting ram reciprocable in said head, a press platen connected to be actuated by said

ram, a press bed mounted in and supported by said press base, the said ram, platen and bed being adapted for insertion through said apertures for assembly within said body, and a plurality of upward acting rams carried by said bed, at least some of which act directly on said platen.

35. A press comprising a hollow cylindrical body, said body including a press head and a press base spaced apart by a wall integral with both, a plurality of apertures in said body one of which opens axially through said base and at least another of which forms a window in said wall, a downward acting ram reciprocable in said head, a press platen connected to be actuated by said ram, a press bed mounted in and supported by said press base, the said ram, platen and bed being adapted for insertion through said apertures for assembly within said body, means guiding said platen in non-rotative reciprocation within said body, and upward acting ram means carried by said bed and at least a portion thereof acting on said platen in opposition to said downward acting ram.

JOHAN A. MULLER.
